US0D1034459S

(12) **United States Design Patent** (10) **Patent No.:** **US D1,034,459 S**
(45) **Date of Patent:** **** Jul. 9, 2024**

(54) **CHARGING UNIT**

(71) Applicant: **Vorwerk & Co. Interholding GmbH**,
Wuppertal (DE)

(72) Inventors: **Jan Delfs**, Bonn (DE); **Felix Thies**,
Wuppertal (DE); **Thomas Lessel**,
Velbert (DE)

(73) Assignee: **Vorwerk & Co. Interholding GmbH**,
Wuppertal (DE)

(**) Term: **15 Years**

(21) Appl. No.: **29/864,653**

(22) Filed: **Jun. 9, 2022**

(30) **Foreign Application Priority Data**

Dec. 10, 2021 (EM) 008793590-0001

(51) **LOC (14) Cl.** **13-02**

(52) **U.S. Cl.**

USPC **D13/108**

(58) **Field of Classification Search**

USPC D13/103, 107, 108, 118, 119, 199;

D14/432, 434; D34/7; D32/25, 30, 31

CPC H02J 7/0044; H02J 7/0045; A47L 11/24;

A47L 9/2815

See application file for complete search history.

(57) **CLAIM**

The ornamental design for a charging unit, as shown and described.

DESCRIPTION

FIG. 1 is a top view of the charging unit showing our new design;

FIG. 2 is a bottom view thereof;

FIG. 3 is a right side view thereof;

FIG. 4 is a left side view thereof;

FIG. 5 is a front view thereof;

FIG. 6 is a back view thereof; and,

FIG. 7 is a top perspective view thereof.

The broken lines in the drawings depict portions of the charging unit that form no part of the claimed design.

1 Claim, 5 Drawing Sheets
